UNITED STATES PATENT OFFICE.

WINFIELD S. BOSLEY, OF CHICAGO, ILLINOIS, ASSIGNOR TO THE WESTERN ELECTRIC COMPANY, OF SAME PLACE.

ARC-LAMP HANGER.

SPECIFICATION forming part of Letters Patent No. 566,652, dated August 25, 1896.

Application filed February 13, 1896. Serial No. 579,142. (No model.)

To all whom it may concern:

Be it known that I, WINFIELD S. BOSLEY, a citizen of the United States, residing at Chicago, in the county of Cook and State of Illinois, have invented a certain new and useful Improvement in Arc-Lamp Hangers, (Case No. 2,) of which the following is a full, clear, concise, and exact description, reference being had to the accompanying drawings, forming 10 a part of this specification.

My invention relates to an arc-lamp hanger; and its object is to provide a hanger whereby the lamp may be raised and lowered and automatically thrown into and out of circuit.

According to my invention the lamp is suspended from a drum or roller, means being provided for rotating the drum to wind thereon or unwind therefrom the cords or cables from which the lamp is suspended. To the 15 suspending-cords is attached the cross-piece, which, when the lamp is raised, comes in contact with a pivoted lever to rotate the same and actuate a switch which throws the lamp into circuit. When the lamp is lowered, the lever is moved to cut the lamp completely from circuit and to close a by-path to complete the circuit about the lamp.

I will describe my invention in connection with the accompanying drawings, in which—

Figure 1 is a view in elevation of the hanger of my invention as seen from one side. Fig. 2 is a similar view as seen from the opposite side. Fig. 3 is a view in section on line 3 3, Fig. 1, the drum being removed. Fig. 4 is a 30 longitudinal sectional view of the hanger. Fig. 5 is a transverse sectional view thereof on line 5 5, Fig. 4.

Like letters refer to like parts throughout the different figures.

Upon a base-board *a* and insulated therefrom are mounted the standards or bearings *b b'*, in which the roller or drum *c* is journaled to rotate. The roller may be of any desired construction and in the present instance is shown as composed of a cylinder of wood, upon the ends of which are provided metallic plates *c' c''*, which, as the drum rotates, make electrical connection with the bearings *b b'*, respectively. To the plate *c'* 45 is electrically connected the end of the cable *d*, the cable then being wound about the

drum and extending downward to the binding-post of the lamp. The cable *d'* is electrically connected with the plate *c''*, and after winding about the drum extends downward 55 and is connected with the opposite binding-post of the lamp. A rope or cord *f* is wound about the central part of the drum and extends downward, whereby it may be grasped to rotate the drum and raise the lamp. Upon 60 the drum is provided a ratchet-wheel *g*, with which a pawl *g'* normally engages, the pawl being provided with an extended end *g''*, adapted to be engaged by the cord *f* to move the pawl out of engagement with the ratchet-wheel. Upon the base-board *a* and insulated therefrom are mounted springs *h h'*, binding-posts *h'' h'''* being provided, one in connection with each of the springs, to which binding-posts the incoming and outgoing 65 wires *h⁴ h⁵* are connected. The ends of the springs *h h'* normally rest in contact with the upturned ends of a metallic strip *h⁶*, which is mounted upon and insulated from the base-board *a*. When in this position, 70 the circuit may be traced from one binding-post through the springs and strip *h⁶* to the opposite binding-post, the lamp being thus cut out. Upon the base-board *a* are mounted springs *i i'*, the springs being insulated 75 from the base-board and their ends disposed, respectively, opposite the ends of springs *h h'*. The spring *i* is connected by a conductor *m* with the bearing *b*, while spring *i'* is connected by a conductor *m'* with the bearing *b'*. 80 The ends of said springs *i i'* rest upon an insulating-block *k*, carried upon the end of a lever *k'*, pivoted at *k²*. The opposite end *k³* of the lever is extended downward, the lower end being bent outward, as shown in Fig. 5. 85 Opposite arm *k³* of the lever *k'* is provided an arm or standard *k⁴*, mounted upon the casing *k⁵*, that incloses the drum, said standard having an oblique lower end.

When the lamp is raised, the cross-piece *l*, 90 secured to the cables *d d'*, passes between the standard *k⁴* and the arm *k³* of lever *k'*, thus rotating said lever upon its pivot to thereby bring the springs *i i'* into contact, respectively, with the springs *h h'*. Circuit may now be 95 traced from incoming wire *h⁴* to binding-post *h²*, thence to spring *h*, spring *i*, by conductor

m to the bearing *b*, thence to cable *d*, through the lamp *e* to cable *d'*, thence to bearing *b'*, conductor *m'*, spring *i*, spring *h'*, binding-post *h³* to the outgoing wire *h⁵*, the lamp being thus connected in circuit.

When the lamp is lowered, the cross-piece *l* is moved from between the standard *k⁴* and arm *k³* and the resiliency of springs *i i'* rotates the lever *k'* upon its pivot to break the contact between the pairs of springs *h i* and *h' i'* and permit the springs *h h'* to make contact with the upturned ends of the strip *h⁶*, to thereby cut out the lamp.

Having thus described my invention, what I claim as new, and desire to secure by Letters Patent, is—

1. The combination with a pair of springs connected, respectively, with the opposite sides of the light-circuit, of a short-circuiting strip with which said springs are normally in contact, a second pair of springs disposed, respectively opposite said first-mentioned springs and connected with the opposite sides of the lamp, a pivoted lever adapted, when rotated, to move said first-

mentioned springs out of contact with said short-circuiting strip and into contact with said second-mentioned springs, and a cross-piece carried upon the cables from which the lamp is suspended adapted to engage and 30 rotate said lever, substantially as described.

2. The combination with the springs *h h'* mounted upon the base-board, of the short-circuiting strip *h⁶* with which said springs *h h'* normally make contact, springs *i i'* with their 35 ends disposed respectively opposite the ends of springs *h h'*, the pivoted lever *k'* carrying insulating-block *l* upon which said springs *i i'* rest, the end *k³* of said pivoted lever *k'* being extended downward, the standard *k⁴* and the 40 cross-piece *l* secured to the cables from which the lamp is suspended adapted to be passed between said standard *k⁴* and arm *k³* of the lever, substantially as described.

In witness whereof I hereunto subscribe my 45 name this 28th day of September, A. D. 1894.

WINFIELD S. BOSLEY.
